INFANT'S FEEDING SPOON OR THE LIKE

Karl Henry Pearson, Jr., R.D. 1, Prosperity, Pa. 15329

Filed Jan. 18, 1973, Ser. No. 324,774

Term of patent 14 years

Int. Cl. D7—03

U.S. Cl. D7—141

Fig.2.

FIG. 1 is a top, perspective view of an infant's feeding spoon or the like, embodying my new design; and

FIG. 2 is a bottom, perspective view thereof.

I claim:

The ornamental design for an infant's feeding spoon or the like, substantially as shown and described.
